UNITED STATES PATENT OFFICE.

JOHN E. LAGERGREN, OF NEW YORK, N. Y.

TROLLEY-POLE.

No. 811,153.

Specification of Letters Patent.

Patented Jan. 30, 1906.

Application filed May 25, 1905. Serial No. 262,179.

To all whom it may concern:

Be it known that I, JOHN E. LAGERGREN, a citizen of the United States, residing in the borough of Brooklyn, in the city of New York, county of Kings, and State of New York, have invented certain new and useful Improvements in Trolley-Poles, of which the following is a specification, reference being had therein to the accompanying drawings, which form a part thereof.

My invention relates to trolley-poles, and more particularly to a class of such embodying safety appliances to avoid injury to the trolley, to cross-wires, or to the pole itself through the escape of the wheel from the trolley.

The main object of the invention is to provide a trolley-pole which while being perfectly free to follow the trolley irrespective of variations in its height or of its sagging between supports will instantly become fixed or locked when the pressure of the trolley is entirely removed from the wheel, thus avoiding damage to the trolley, to cross-wires, or to the pole itself by reason of the pole flying off the trolley.

A further object is to provide a trolley-pole wherein when once locked as above the locking mechanism cannot be released by a further pressure on the pole.

A still further object is to provide a trolley-pole which when locked as above will be automatically released by the lowering of the pole through the rope carried by the head to permit the replacement of the wheel on the trolley.

A still further object is to provide a simple locking or clutch mechanism which may be actuated substantially instantly irrespective of the position of the pole, thus avoiding such material movement of the pole-head as would tend to bring it into the plane of cross-wires or of cross-trolleys.

A still further object is to provide a locking or clutch mechanism which will not be exposed to the elements to an extent to render it inoperative; and a still further object is to provide a locking or clutch mechanism which may be applied to the type of trolley-pole now commonly used without material alteration or expense.

The invention consists, primarily, in the combination, in a trolley-pole, of a base, a trolley-pole mounted thereon, an automatic lock or clutch mechanism whereby said pole is normally locked in relation to said base,

a movable trolley-head and means actuated by said trolley-head whereby pressure on said head will release said lock or clutch, and in such other novel features of construction and combination of parts as are hereinafter set forth and described, and more particularly pointed out in the claims hereto appended.

Referring to the drawings, Figure 1 is a side elevation of a trolley-pole embodying my invention. Fig. 2 is a view, on a larger scale, of the lower end of the trolley-pole shown in Fig. 1, with one side of the base removed and the pole shown in section to disclose the locking or clutch mechanism and the means adjacent thereto for releasing same. Fig. 3 is a view of the trolley-head with the pole adjacent thereto in section to disclose the construction whereby the locking or clutch mechanism is released through pressure on the said head. Fig. 4 is a cross-section of the trolley-base, the socket-fitting mounted therein, and the locking or clutch mechanism; and Fig. 5 is a perspective view of the locking or clutch mechanism, one side thereof being broken away to disclose the actuating mechanism of the band.

Like letters refer to like parts throughout the several views.

In the drawings, *a* refers to the base for the trolley-pole, being provided with side webs *b* and carrying the oppositely-acting springs *c* *c'*, acting upon the offset arm *e'* of the socket fitting to the trolley-pole. This base is shown as being adapted to swivel on the base-plate *d*, such being a common (but not exclusive) manner of mounting the pole to permit it to be reversed. Fitted in the socket-fitting *e* is an ordinary tubular pole *f*. This general construction is, as now ordinarily in use, my invention relating more particularly in the application thereto of a locking or clutch mechanism, whereby said pole is not permitted to rise under the influence of the spring *c* in case the trolley-wheel escapes from the trolley. This mechanism comprises, broadly considered, a lock or clutch acting adjacent to the bearings for the socket-fitting or the bottom of the pole, a movable trolley-head carrying the wheel, and means whereby the movement of the said head, either through the spring *c* forcing the wheel or other contact into engagement with the trolley or through the trolley-rope, will release said lock or clutch, so as to permit the unrestricted oscillation of the pole necessary to have it follow

the trolley or be replaced thereon. The preferred form of this mechanism is that shown in the accompanying drawings, wherein the socket-fitting *e* is provided with a forked end, 5 by means of which the said fitting is pivotally mounted between the side webs *b* by means of the axle *b'*, fixed with relation to said webs *b*. Keyed to said axle *b'* in the forked end of the fitting *e* is a drum *g*. Encircling 10 this drum *g* is a band *h*, the ears *h' h²* of which are preferably forked, the latter being extended, so as to be substantially alined with the former, while allowing sufficient play or clearance to close the band to set the brake or 15 clutch, said ears both being fitted within the forked end of said socket-fitting. Mounted between these forked ears *h' h²* is a plate *i*, pivotally connected to the said ears, respectively, in a manner to insure movement there- 20 of about either of said pivots, drawing said ears together to close said band or spreading them to release the same from its engagement with the said drum. Said plate has an arm *i'* projecting into and adapted to engage 25 the pole *f* in a manner to cause the slightest upward movement of said pole-and-socket-fitting *e* to raise said arm and close the band *h* upon the drum *g*. The plate *i* and ear *h²* being rectangular, this movement causes one 30 corner thereof to project slightly below the socket *e*.

The pole *f* carries adjacent to the socket *e* bearings for a lever *j*, one arm of which engages the aforesaid projecting corner of the 35 plate *i* and ear *h²*, and the other arm of which is projected at an angle therefrom through a way *f'* into said pole, being beveled at *j'*, as shown. Fitted in the hole *f* is a bearing-block *f²*, in which is mounted a rod *k*, one end 40 of which is provided with an enlarged conical head *k'*, engaging the beveled end *j'* of the lever *j*, and the other end of which projects from the top of the pole. Fixed to said rod is a collar *k²*, between which and the block 45 *f²* is seated a spring *k³*, tending to normally project the end of said rod *k* from said pole and leave the lever *j* free to be so rocked as to permit the plate *i* to move sufficiently to close the band *h* upon the drum *g*, thus tending to 50 normally lock or set said lock or clutch.

The trolley-head comprises a bell-crank lever, one arm of which is an ordinary yoke *l*, in which the wheel *m* is mounted in the usual manner. This lever, however, is movable, 55 being pivotally connected to the pole *f*, with the other arm *n* engaging the projected end of the rod *k*. This arm is provided with an extension *n'*, adapted to have the trolley-rope *o* attached thereto.

60 The operation of the structure heretofore described is substantially as follows: The pole *f* is adapted to be raised and subjected to constant pressure to hold the wheel *m* on the trolley by the spring *c*, the spring *c'* tending 65 to modify the action of said other spring in

the usual and well-known manner. This action turns the socket-fitting *e* on the axle *b'*, said axle and the drum *g* thereon remaining stationary. This tends to normally press the pole *f* adjacent to the said fitting *e* against 70 the arm *i'*, thus drawing the ears *h' h²* together through the movement of the plate *i* and setting the band *h* upon the drum *g*, thus locking the said arm, and through it the pole *f*, in position, projecting the said plate *i* and 75 the ear *h²* below the socket *e* and forcing the beveled end *j'* of the lever *j* through the way *f'* into engagement with the head *k²* of the rod *k*. The pole *f* and its socket *e* are capable of slight downward movement independently 80 of the arm *i'* so that even when the band *h* is set the pressure on said arm may be relieved sufficiently by the further depression of the pole to so release said band as to permit still further depression thereof. It will 85 be observed that at all times the tendency of the locking or clutch mechanism is to overcome the tendency of the spring *c* to raise the pole, thus necessitating the employment of means controlling this mechanism while the 90 trolley-wheel is in proper engagement with the trolley. In practice it is required that the pole be capable of rising and being depressed with great freedom to permit the trolley-wheel *m* to follow the trolley and 95 adapt itself to the variations in the height of the wire and to the play incidental to a trolley that sags between its supports or supporting cross-wires. The tendency of the locking or clutch mechanism to prevent this necessary movement is overcome so long as the 100 wheel *m* is on the trolley, the pressure exerted by the spring *c* forcing the said wheel and the arm *n* of the bell-crank lever carrying same downward, depressing the rod *k* against 105 the tension of the spring *k³* until the conical head *k'* thereof acts on the beveled end *j'* to force out that arm of the lever *j*, and through the action of the other arm thereof to force in 110 the projecting corners of the plate *i* and the ear *h²*. This spreads the ears of the band *h* and permits the unrestricted movement of the pole *f* in either direction. This forces the end of the arm *i'* into engagement with the pole *f*, and so long as the pressure is exerted 115 on the rod *k* by the continuance of the wheel *m* on the trolley this condition will continue. Instantly with the escape of the wheel *m* from the trolley, however, the spring *k³* releases the beveled end *j'* and permits the 120 spring *c* to raise the pole slightly, carrying with it the arm *i'*, thus closing the band *h* upon the drum *g* and locking the pole against all further upward movement, all parts assuming their normal position. The arm *i'*, 125 projecting into the pole *f*, affords a sufficient leverage to insure the proper frictional engagement of the band *h* and the drum *g*, inasmuch as the band-brake or other similar friction clutch or lock may be set accurately, 130

the degree of movement required to set same is very small, and the quantity of movement of the pole before it operates will not be sufficient to cause it to project so as to contact 5 with cross-wires squarely, and a glancing blow will suffice to merely oscillate the head upon its pivot or further depress the pole. Under ordinary circumstances, however, the wheel in leaving the trolley is forced down- 10 ward sufficiently to permit the lock or clutch to operate before the pole rises to a height sufficient to engage or contact with a cross-wire, and in case the movable wheel-support projects above the level of the said 15 wires it will, as stated, give with the contact, and thus not endanger the wire. When the locking or clutch mechanism is once set to enable the wheel *m* to be replaced on the trolley, it is necessary to release said mechanism 20 to permit the pole *f* to oscillate freely under the tension of the spring *c*. This is accomplished by merely using the rope *o* in the usual manner, the arm *n* of the bell-crank lever carrying the wheel *m* being actuated by 25 the pull on the said rope to force the rod *k* downward and release the band *h* in the same manner as though through pressure on the wheel *m*.

It will be observed that no delicate mechanism or balanced springs are required in this structure and that the various elements are so disposed as to be more or less protected from the elements and not to present unsightly attachments. The apparatus is not 30 liable to material wear, and the parts are inexpensive to produce and easily applied to the ordinary trolley-pole now in general use.

While I have shown and described my invention in connection with certain specific 40 clutch mechanisms and means actuating same, I do not wish to be considered as limiting the invention to these minor details, it being apparent that there may be many variations in these details without departing from 45 the spirit and scope of the invention.

Having described the invention, what I claim as new, and desire to have protected by Letters Patent, is—

1. In a trolley-pole, the combination of a 50 base, a spring-pressed pole mounted thereon, an automatic friction lock or clutch mechanism whereby said pole is normally locked in relation to said base, a movable trolley-head, and means actuated by said trolley-head 55 whereby pressure on said head will release said lock or clutch.

2. In a trolley-pole, the combination of a base, a spring-pressed pole mounted thereon, a friction-drum carried by said base, a friction-brake carried by said pole, means whereby said brake is normally set, a movable trolley-head and means actuated by said trolley-head whereby pressure on said head will release said brake.

65 3. In a trolley-pole, the combination of a

base, a spring-pressed pole mounted thereon, a friction-drum carried by said base, a friction-band encircling said drum, provided with projected ears, a plate pivoted to said ears respectively, means whereby said plate may 70 be actuated by said pole to close said band, a movable trolley-head, and means actuated by said trolley-head whereby pressure on said head will actuate said plate to release said band.

4. In a trolley-pole, the combination of a base, a spring-pressed pole mounted thereon, a friction-drum carried by said base, a friction-band encircling said drum provided with projected ears, a plate pivoted to said 80 ears respectively, an arm on said plate projected into and engaging said pole, whereby upward movement of said arm by said pole will close said band, a movable trolley-head, and means actuated by said trolley-head 85 whereby pressure on said trolley-head will actuate said plate to release said band.

5. In a trolley-pole, the combination of a base, a spring-pressed pole mounted thereon, an automatic friction lock or clutch mechanism 90 whereby said pole is normally locked in relation to said base, a rod mounted on said pole, a spring whereby said rod is normally projected beyond said pole, a pivoted trolley-head engaging said rod, and means whereby 95 pressure on said trolley-head will through the depression of said rod, release said lock or clutch mechanism.

6. In a trolley-pole, the combination of a base, a spring-pressed pole mounted thereon, 100 an automatic friction lock or clutch mechanism whereby said pole is normally locked in relation to said base, a rod mounted on said pole, a spring whereby said rod is normally projected beyond said pole, a bell-crank lever, the opposite arms of which are respectively adapted to receive a trolley-wheel and to engage said rod, and means whereby pressure on said trolley-head will through the depression of said rod release said lock or clutch 105 mechanism.

7. In a trolley-pole, the combination of a base, a spring-pressed pole mounted thereon, a friction-drum carried by said base, a friction-band encircling said drum provided 115 with projected ears, a plate pivoted to said ears respectively, an arm on said plate projected into and engaging said pole whereby upward movement of said arm by said pole will close said band, and project said plate 120 from said pole, a rod mounted on said pole, a spring whereby said rod is normally projected beyond said pole, a lever mounted on said pole, the opposite arms thereof respectively engaging said plate, and being beveled to be 125 actuated by said rod, and a pivoted trolley-head engaging said rod whereby pressure on said trolley-head will through the depression of said rod actuate said lever to release said band.

8. In a trolley-pole, the combination of a base, a spring-pressed pole mounted thereon, a friction-drum carried by said base, a friction-band encircling said drum provided with projected ears, a plate pivoted to said ears respectively, an arm on said plate projected into and engaging said pole whereby upward movement of said arm by said pole will close said band, and project said plate from said pole, a rod mounted on said pole, a spring whereby said rod is normally projected beyond said pole, a lever mounted on said pole, the opposite arms thereof respectively engaging said plate and being beveled to be actuated by said rod, and a bell-crank lever

mounted on said pole, the opposite arms of which are respectively adapted to receive a trolley-wheel and to engage said rod and have a rope secured thereto, whereby pressure on said trolley-head will through the depression of said rod actuate said lever to release said band. 20

In witness whereof I have hereunto affixed my signature, this 24th day of May, 1905, in the presence of two witnesses.

JOHN E. LAGERGREN.
